UNITED STATES PATENT OFFICE.

WASHINGTON BERRY, OF CHICAGO, ILLINOIS.

SOAP-MOLD.

SPECIFICATION forming part of Letters Patent No. 695,027, dated March 11, 1902.

Application filed July 31, 1901. Serial No. 70,364. (No model.)

To all whom it may concern:

Be it known that I, WASHINGTON BERRY, a citizen of the United States, residing at Chicago, in the county of Cook and State of Illinois, have invented certain new and useful 5 Improvements in Soap-Molds, of which the following is a specification.

My invention relates to improvements in that class of apparatus which is used in the 10 production of bars of soap containing inserts or floats centered and symmetrically spaced within said bars in such manner that said bars may be cut into cakes, each containing an insert or float properly centered therein.

15 The object of my invention is to simplify the manufacture of cakes of soap having inserts properly centered therein.

Another object of my invention is to devise apparatus for the production of such 20 cakes of soap which shall be strong, simple, and inexpensive.

These and such other objects as may hereinafter appear are attained by the devices illustrated in the accompanying drawings, in 25 which—

Figure 1 indicates a vertical sectional view of my improved mold, containing a number of inserts mounted and spaced upon a mounting-rod. Fig. 2 indicates a plan view of the 30 cap or cover of my mold. Fig. 3 is a plan view of my spacing device. Fig. 4 is a cross-sectional view of the spacing device on the line 4 4 of Fig. 3, and Fig. 5 is a similar section on the line 5 5 of Fig. 3.

35 Like letters of reference indicate the same parts in the several figures of the drawings.

Referring by letter to the accompanying drawings, A indicates a cylinder or tube, which may be formed of thin sheet metal. 40 The lower end of this cylinder may be inserted in a cake of soap or similar material.

In the preferred form of my mold, as shown in Fig. 1, the lower end of the cylinder A is mounted upon a base-block B, in which is 45 embedded a packing-ring C of rubber or like material. Upon the base-block B is mounted a base-plate D, having a screw-threaded central opening d for engaging the screw-threaded lower end of the rod E, upon which are 50 mounted the inserts F. The upper end of the rod E passes through a central opening in the cap or cover G and engages a knob or

handle H. The cap G is preferably formed with an annular shoulder g, which fits within the upper end of the cylinder A, and with an 55 annular flange g', which extends over the end of the cylinder A.

For stiffening the cylinder A, as well as for providing a convenient means for holding it when the molded soap is to be forced out of 60 the cylinder, the cylinder A may be provided with flanged rings a b. The cap or cover G is provided with an annular opening g².

My spacing device consists of a trough-like block I, which is provided on its upper face 65 with a longitudinal groove, which is preferably V-shaped. In this groove are located movable spacing-blocks J, provided with open slots j.

In preparing my mold the spacing-blocks 70 J are set in position in the trough I, and one of the inserts F is placed between every two of the spacing-blocks. The contour of the bottom of the trough I will serve to properly center each of the inserts F, and after the inserts are in place and the spacing-blocks and the inserts between them are brought closely together the rod E is inserted longitudinally 75 through the slots in the spacing-blocks and the central openings in the inserts. The openings 80 in the inserts are made of such size with relation to the rod E that while the rod may be freely inserted therethrough there will be sufficient friction between the inserts and the rod that the inserts will retain their position on 85 the rod after the rod is lifted up through the slots j' and away from the spacing-blocks.

The rod E is then inserted in the cylinder A, and the lower end thereof being screwed into the screw-threaded opening d in the base-plate D the flange of the cover G is thereby 90 drawn tightly against the upper end of the cylinder A, and the lower end of the cylinder A is forced into tight contact with the packing-ring C. Liquid soap is now poured into 95 the mold through the opening g². When the soap hardens, the rod E is unscrewed from the base-plate D and is withdrawn from the mold and from the inserts F. The cylinder A is thereby disengaged from the base-block 100 B and from the cap G and is left filled with a bar of soap containing the inserts F accurately centered and spaced therein. This bar of soap may now be forced out of the

mold by any convenient means and cut into cakes, each containing an insert, which cakes may be subsequently pressed into any desired shape, such pressing serving to close 5 the small opening through the cake left by the withdrawal of the rod E.

Of course the block I may be grooved in various shapes, as may be deemed convenient or expedient or as may be required by 10 the different contours of the inserts which may be used. So, also, the contour and position of the spacing-blocks J may be varied or the trough I and spacing-blocks may be formed of one piece, in which event the 15 spaces between the spacing-blocks will be represented by cross-grooves in the trough I, intersected by one long central groove corresponding to the slot j'. So, also, the broad idea of my invention may be utilized by using 20 a wire, cord, or similar means for supporting the inserts, as well as for tightly securing the ends of the mold in place; but these and similar modifications are contemplated by my invention.

25 Having thus fully described my invention, what I claim, and desire to secure by Letters Patent, is—

1. In a soap-mold, the combination with a 30 easing, of an insert-support, means for securing said support in a desired position in said easing, and a plurality of inserts strung upon said support, substantially as described.

2. In a soap-mold, the combination with a 35 easing, of a support extending centrally

therethrough, and a plurality of inserts mounted 35 ed and regularly spaced apart upon said support and within said casing, substantially as described.

3. In a soap-mold, the combination with a base of a plate mounted thereon, a casing extending over said base-plate and engaging said base, a rod extending centrally through said casing, a top plate mounted upon said rod, means upon said rod for engaging said base-plate and a plurality of inserts mounted 45 directly upon said rod, substantially as described.

4. The combination with a soap-mold, of a spacing device comprising a trough and a plurality of adjustable slotted spacing-blocks, 50 substantially as described.

5. The combination with a soap-mold of a spacing device, comprising a longitudinal block, a plurality of transverse slots therein, 55 said slots being accurately spaced apart and a central longitudinal slot, substantially as described.

6. In a soap-mold, the combination with a base, a casing mounted thereon, a rod extending longitudinally through said casing, 60 a top plate carried by said rod, means upon said rod for engaging said base, and a plurality of inserts mounted upon said rod, substantially as described.
